UNITED STATES PATENT OFFICE

118,465

DESIGN FOR A CHAIR

Grant Wood, Iowa City, Iowa, assignor to Henry Lubben, Cedar Rapids, Iowa

Application October 5, 1938, Serial No. 80,276

Term of patent 7 years

To all whom it may concern:

Be it known that I, Grant Wood, a citizen of the United States, residing at Iowa City, in the county of Johnson and State of Iowa, have invented a new, original, and ornamental Design for a Chair, of which the following is a specification, reference being had to the accompanying drawings, forming part thereof.

I claim:

The ornamental design for a chair, as shown.

GRANT WOOD,
